UNITED STATES PATENT OFFICE.

WILLIAM D. ACKLEY, OF HENRIETTA, TEXAS, ASSIGNOR TO FRANK HOLTON & COMPANY, OF CHICAGO, ILLINOIS, A CORPORATION OF ILLINOIS.

TROMBONE.

1,330,831.

Specification of Letters Patent. Patented Feb. 17, 1920.

Application filed February 17, 1917. Serial No. 149,242.

To all whom it may concern:

Be it known that I, WILLIAM D. ACKLEY, a citizen of the United States, residing at Henrietta, in the county of Clay and State 5 of Texas, have invented certain new and useful Improvements in Trombones, of which the following is a specification.

This invention relates to a musical instrument slide and is more particularly designated as a bearing or stocking for a trombone or other similar instruments in which it is desirable to provide a smooth bearing for the slideable part of the instrument.

The invention consists in making the 15 bearing or stocking of such a shape that it will have all of the advantages and none of the disadvantages both of a long stocking or bearing and a short stocking. The invention further consists in a novel construction, combination and arrangement of the parts as set forth in the following 20 claims.

In the accompanying drawing,

Figure 1 is a view with a portion broken 25 away, showing the fixed and slideable parts of a trombone;

Fig. 2 is an enlarged detail of the stocking shown in Fig. 1 with the end of the slide shown in broken outline; and

30 Figs. 3, 4 and 5 are modifications of the stocking.

In trombones it is desirable that the slide of the instrument shall have a smooth and quick slide action in one position as well as 35 in the others. It is found that a short stocking or bearing at the end of the fixed tube connected to the mouth piece, will give a quicker slide action because of the fact that there is a shorter bearing surface than if the 40 stocking is longer. One objection to the short stocking, however, is that in the outermost positions of the trombone slide the weight of the outer end of the slide tends to bear down the end, and bearing upon the 45 stocking which supports it unevenly, the slide is apt to have an uneven or jerky action in its outermost positions. This can be minimized by making the stocking of sufficient length, but if the stocking is made 50 too long the friction will be so great that it does not have a quick or smooth action in the other positions.

In the present invention all of the objections both to the short stocking and to

the long stocking are overcome by making 55 one side of the stocking of about the usual length of the small stocking and the other side of about the length of the long stocking.

Referring now more particularly to the 60 drawing, a mouth piece 1 is attached to a tubular member 2 and at the end of the tubular member is a stocking 3. Movable over the tubular member 2 and upon the stocking 3, which it closely fits, is a slide 4 comprising two parallel portions, and a connecting curved portion 5. Although the stocking 3 is shown only in connection with the tubular member 2, it should be understood that the other fixed member 6 upon 70 which the slide 4 is movable may also be provided with such a bearing. It should be understood, furthermore, that in playing position the mouth piece 1 and the tubular member 2 are ordinarily horizontal or substantially so, and above the tubular member 6. The stocking 3, as shown more clearly by Fig. 2, has its outer end 7 cut at right angles, but the inner end has an inclined portion 8 with a shoulder 9 on the 80 upper side and an extremity 10 on the lower side, which does not come to a sharp point but embraces the arc of a circle at the end, as does also the shoulder 9. A slightly different form is shown in Fig. 3 in which the 85 shoulder 9' and the extremity 10' are inclined instead of being transverse to the longitudinal axis of the stocking as in Fig. 2. In the form shown by Fig. 4, the inner extremity is simply beveled off at an angle 90 and in the form shown by Fig. 5 the stocking is cut down about half-way, forming the shoulder 12, and the lower or longer portion 13 of the stocking is made up of the remainder thereof.

95 It is obvious that in all of these forms the upper side of the stocking is much shorter than the lower side, and therefore gives smooth and quick action to the slide with a minimum of friction.

100 When the slide is in its outermost playing positions it tends to twist downward on the stockings. This downward twisting of the slide causes the latter to bear down on the upper surface of the stocking near the outer end or the end adjacent the outer end of the tubular member 2 and causes an upward pressure by the slide on the inner end of the

lower side of the stocking. In long stocking constructions this downward twisting of the slide greatly increases the friction, due to the large engaging surfaces of the slide and stocking. In short stocking constructions the short stocking is so short that the ends of the latter tend to cut into or lock the slide. Hence, in both the short stocking and the long stocking constructions difficulty is experienced in having the slide move easily and smoothly in its outer playing positions. In a construction as set forth in this application by cutting away the upper side of the inner end of the stocking, the friction between the stocking and slide are reduced to a minimum and the long lower side of the stocking prevents the tendency of the slide to lock on the stocking. This construction therefore overcomes the objections above referred to in both the short and long stocking constructions.

Another feature of importance in all of the stockings shown is that dirt pockets are avoided by having continuous surfaces for joining the upper and lower, or shorter and longer portions of the stocking. By inclining those portions of the stocking which join the short and long sides thereof, cutting edges are, to a great extent, avoided, and the lubricant for the slide is more evenly distributed, the inclined portion tending to throw it upwardly thereby equalizing the distribution.

The stockings are commonly formed of tubular material which is secured to the end of a pipe or tubular member by soldering, brazing, or in any other suitable manner.

My stocking may be applied or substituted in place of a long or short stocking in a trombone already in use, as well as being applied to new instruments.

I claim:

1. An article of manufacture comprising

a stocking for trombones having its upper side materially shorter than its lower side. 45

2. In a trombone, the combination of a tubular member, a tubular stocking disposed on the tubular member and having its upper side considerably shorter than its lower side when in playing position, and a slide 50 bly mounted on the stocking.

3. In a trombone, the combination of a tu-
bular member, a tubular stocking disposed
on the tubular member and having its end
adjacent one end of said tubular member 55
substantially in a plane at right angles to the
axis of the stocking and its other end gen-
erally inclined to said axis with the upper
side of the stocking considerably shorter
than the lower side of such stocking, and a 60
slide movably mounted on the stocking.

4. An article of manufacture which con-
sists of a bearing stocking for a trombone,
cylindrical in shape and cut off at right an-
gles at one end, and materially shorter on 65
one side than on the opposite one to form
a longer bearing for one side of a trombone
slide than for the opposite side.

5. The combination in a trombone of a
tubular supporting member, a slide movable 70
thereon, and a supporting stocking placed at
the end of the member and formed at its
inner end with the side which is uppermost
in the playing position considerably less in
length than the opposite or lowermost side 75
so that in the outermost playing positions of
the slide the end of the latter will bear
against the said longer side of the stocking.

In testimony whereof I have signed my
name to this specification, in the presence of 80
two subscribing witnesses, on this twelfth
day of February, A. D. 1917.

WILLIAM D. ACKLEY.
